UNITED STATES PATENT OFFICE.

EDGAR G. TEED, OF BUTTE, MONTANA.

OIL-BURNER.

1,251,839.

Specification of Letters Patent.

Patented Jan. 1, 1918.

Application filed March 23, 1917. Serial No. 156,972.

To all whom it may concern:

Be it known that I, EDGAR G. TEED, a citizen of the United States, residing at Butte, in the county of Silver Bow and 5 State of Montana, have invented certain new and useful Improvements in Oil-Burners, of which the following is a specification.

This invention relates to oil burners and more particularly to a device for converting 10 fuel oil into a highly inflammable spray and ejecting the spray in a manner that will permit it to be ignited for producing a flame of intense heat.

One of the objects of the invention is to 15 provide an oil burner of this character constructed to receive oil, super-heated steam, and air and to properly cause the said elements to intermingle whereby an inflammable spray may be produced for the purpose of providing a jet of flame having an extremely intense heat.

As a further object of the invention, the device includes the provision of a mixing 20 chamber connected with a suitable supply pipe designed to convey both steam and oil into the mixing chamber whereby an atomized liquid may be formed for being ejected from the chamber in the form of a tubular swirling column.

Another object of the invention is the 25 provision of a discharge tube for conveying a swirling column of inflammable spray outwardly in the form of a jet having considerable force and associated with an air outlet 30 pipe to prevent the formation of carbon within the outlet pipes when the device is in operation.

The invention also includes the provision 40 of means for permitting the operator to observe the flame whereby it may be properly regulated through suitable adjusting means provided for this purpose.

A further object of this invention is the 45 provision of an oil burner which consists of comparatively few parts and is simple in construction, but durable and well adapted to withstand the rough usage to which devices of this character are ordinarily subjected.

For a full description of the invention 50 and the advantages and merits thereof, reference is to be had to the following description and the accompanying drawings, wherein is illustrated the preferred form of my invention, in which;

Figure 1 is a side elevation showing my invention applied to the front of a boiler.

Fig. 2 is a longitudinal section on the line 2—2 of Fig. 1.

Fig. 3 is a transverse section on the line 3—3 of Fig. 1.

Fig. 4 is a transverse section on the line 4—4 of Fig. 1.

Referring to the drawing, wherein is illustrated the preferred form of my invention, 60 and in which like numerals of reference indicate corresponding parts throughout the several views, the boiler front A is provided with a suitable opening B for the reception of the burner. Mounted in the opening is a 65 bushing 1 having an annular flange 2 engageable with the front surface of the boiler front A, and adapted to be fastened thereto by a plurality of suitable fastening elements 3 in the form of screws, bolts or the like. 70 The interior of the bushing 1 is screw threaded to receive a supporting ring 4 having screw threads on its exterior to register with the screw threads of the bushing 1. The supporting ring 4 has interior screw 80 threads and these receive the screw threads formed on one end of an outer discharge pipe 5.

The retaining ring 4 is integrally formed 85 with the forward wall of the mixing chamber 6 and is, therefore, in the form of a flange embracing the end of the pipe 5. It will be noted that the mixing chamber 6 is of circular formation, and the outer peripheral wall thereof is substantially semi-circular in cross section.

Opposite to the ring or flange 4, the casing is provided with an annular flange 7, extending around a central opening 8 formed in this end of the casing or chamber. The 95 flange 7 has an annular recess, the wall of which is screw threaded to receive the enlarged screw threaded end 9 of an air discharge pipe 10 projecting forwardly and through the opening 8, and through the center of the mixing chamber 6. This air discharge pipe 10 is smaller in diameter than the interior diameter of the pipe 5, and terminates at the end of the pipe 5, thus providing an elongated space between the pipe 105 5 and the pipe 10 which establishes communication between the interior of the mixing chamber 6 and the atmosphere.

The enlarged portion 9 carries a flange 11 engageable with the end of the flange 7. 110

When the enlarged portion 9 is mounted in position in the annular recess formed in the flange 7, a packing space 12 is provided for the reception of a suitable packing 13 for making the joint air-tight. The pipe 10 is extended beyond the enlarged portion to form the air intake tube 14 and its end is provided with screw threads for the reception of a cap 15 which receives a circular panel 16 of glass that will be held in contact with the end of the tube 14, when the cap is mounted in place. This glass panel permits the operator to view the interior of the air discharge pipe whereby the condition of the flame at the end of the pipe may be observed. Rotatably mounted upon the tube 14 is a sleeve 17 having a handle 18 attached for the purpose of imparting a rotary movement to the sleeve. The tube 14 is provided with a plurality of suitable apertures, and the sleeve 17 also has a plurality of apertures adapted to be moved into and out of registration with the apertures in the tube. In this manner, the air received in the tube 25 may be regulated as desired.

One side of the casing or mixing chamber 6 is provided with a projecting portion 19 carrying a neck 20. A central opening in the neck is provided with screw threads for receiving the corresponding screw threads of a fastening head 21 carried at one end of the oil inlet pipe 22. This pipe 22 projects through the central opening in the neck and into the chamber 6 as clearly shown by Fig. 35 of the drawing, and its longitudinal center is preferably disposed at a tangent to the circumferential center line of the space encircling the pipe 10 in the chamber 6. The opposite end of the pipe 22 projects sufficiently beyond the head 21 to receive one end of a T-fitting 23 to which is attached a steam intake pipe 24. An oil intake pipe 25 is extended centrally through the pipe 22, and also through the center of the T-fitting 45 23. An elbow 26 is carried by the outer end of the pipe 25, and a suitable cap 27 is mounted upon the screw threaded end of the pipe 25 and extending slightly into the T-fitting for the purpose of closing the outer 50 end of the same. The elbow 26 may be connected to a suitable source of oil supply, while the pipe 24 will be connected to a source of steam supply.

In use, the device will be operated either 55 singly or in a series according to the type of boiler that is being heated. After mounting the device in position on the front of the boiler, the super-heated steam will be turned on, and the oil will be permitted to flow to 60 the pipe 25. Of course, the steam will pass through the pipe 22 encircling the oil pipe 25, and the intense heat of the steam will heat the pipe 25 to a high temperature, thus causing the oil to be ejected from the end of 65 the pipe 25 in an atomized state. Further-

more, the ejection of the steam from the end of the pipe 22 will create a vacuum in the pipe 25 for the purpose of drawing the inflammable spray from the pipe 25 so that the inflammable spray is forcibly ejected 70 into the mixing chamber 6. The shape of the mixing chamber causes a swirling centrifugal motion to be imparted to the mixture and the same will encircle the pipe 10 and be ejected through the pipe 5 in a tubular column. The handle 18 will be manipulated to govern the air intake openings to admit the proper quantity of air which will be drawn through the pipe 10 by the vacuum created when the steam and oil are ejected 80 from the end of the pipe 5. Thus, it will be seen, that with the force applied to the super-heated steam, the action of the device is entirely automatic with respect to the intake of both the oil and air. At the end of 85 the pipe 5, the mixture is ignited and a smokeless, sootless and practically noiseless jet of flame will be produced that will continue to burn as long as the oil is supplied to the device. The swirling centrifugal motion produced in the mixing chamber is continued through the ejecting pipe so that the inflammable spray is under the influence of this swirling movement at the time of ignition. The jet of air causes a tubular column 90 of flame to be produced, and this is slightly spread so that an unusually intense heat is produced. This motion also prevents the formation of carbon at the end of the pipes and a clean burner is thus produced. 95

From the foregoing it will be observed that a very simple and durable oil burner has been provided, the details of which embody the preferred form. I desire it to be understood however, that slight changes in 105 the minor details of construction may be made without departing from the spirit of the invention or the scope of the claims hereunto appended.

I claim:

1. An oil burner comprising a mixing chamber having central openings formed in each end, a steam inlet pipe extending into the chamber, an oil inlet pipe extending through the said steam inlet pipe, an outlet 115 pipe mounted in one of the said central openings and communicating with the interior of the said chamber, an air pipe mounted in the other of said central openings and extending through the center of 120 the said chamber and through the said outlet pipe, the said casing having a retaining ring embracing the end of the said outlet pipe, and means for receiving the said retaining ring for supporting the said casing. 125
2. An oil burner comprising a mixing chamber having central openings formed in each end, a steam inlet pipe extending into the chamber, an oil inlet pipe extending through the said steam inlet pipe; an outlet 130

5 pipe mounted in one of the said central openings and communicating with the interior of the said chamber, an air pipe mounted in the other of said central openings and extending through the center of the said chamber and through the said outlet pipe, the said casing having a retaining ring embracing the end of the said outlet pipe, a bushing mounted upon the said 10 retaining ring and provided with an annular flange for securing the said bushing to a support.

15 3. An oil burner comprising a mixing chamber having central openings formed in each end, a steam inlet pipe extending into the chamber, an oil inlet pipe extending through the said steam inlet pipe, an outlet pipe mounted in one of the said central openings and communicating with the interior of the said chamber, an air pipe mounted in the other of said central openings and extending through the center of the said chamber and through the said outlet pipe, the said casing having a retaining 20 ring embracing the end of the said outlet pipe, a bushing mounted upon the said retaining ring and provided with an annular flange for securing the said bushing to a support, the opposite end of the said casing having an annular flange surrounding the corresponding opening, the said air pipe being provided with an enlarged portion embraced by and secured to the said annular 25 flange, the said annular flange having a recess for receiving the said enlarged portion, one end of the recess forming a packing space, and a packing mounted in the 30 said space.

35 4. An oil burner comprising a mixing chamber having central openings formed in each end, a steam inlet pipe extending into the chamber, an oil inlet pipe extending through the said steam inlet pipe, an outlet 40 pipe mounted in one of the said central

openings and communicating with the interior of the said chamber, an air pipe mounted in the other of said central openings and extending through the center of the said chamber and through the said outlet pipe, the said casing having a retaining ring embracing the end of the said outlet pipe, a bushing mounted upon the said retaining ring and provided with an annular flange for securing the said bushing to a support, the opposite end of the said casing having an annular flange surrounding the corresponding opening, the said air pipe being provided with an enlarged portion embraced by and secured to the said annular 45 flange, the said annular flange having a recess for receiving the said enlarged portion, one end of the recess forming a packing space, and a packing mounted in the 50 said space.

5. An oil burner comprising a mixing chamber provided in a casing of circular formation, an air pipe and an outlet pipe extending axially from the said casing, and an oil pipe connected to and projecting into 55 the casing substantially tangentially thereof.

6. An oil burner comprising a mixing chamber provided in a casing of circular formation, an air pipe and an outlet pipe extending axially from the said casing, and an oil pipe connected to and projecting into 60 the casing substantially tangentially thereof, and a steam pipe embracing the said oil pipe and in spaced relation thereto.

In testimony whereof I affix my signature 65 in presence of two witnesses.

EDGAR G. TEED.
